UNITED STATES PATENT OFFICE.

THOMPSON D. HART, OF PHILADELPHIA, PENNSYLVANIA.

IMPROVEMENT IN EXPLOSIVE SHELLS.

Specification forming part of Letters Patent No. 41,844, dated March 8, 1864.

To all whom it may concern:

Be it known that I, THOMPSON D. HART, of the city and county of Philadelphia, State of Pennsylvania, have invented a new and Improved Mode of Constructing Explosive Shells; and I hereby declare the following to be a full, clear, and exact description of the same, reference being had to the accompanying drawings, and to the letters of reference marked thereon.

My invention consists in securing a number of bars longitudinally around the main body of the shell, in the manner as hereinafter described.

In order to enable others to practice my invention, I will proceed to describe its construction.

On reference to the accompanying drawings, which forms a part of the specification, Figure 1 is a longitudinal section through the center of the shell; Fig. 2, a transverse view of the same across the line 1 and 2, Fig. 1.

Similar letters refer to similar parts throughout the several views.

A A is the main body of the shell; C C, a number of bars arranged around the same; B, the bore of the same, (or the chamber for containing the explosive material;) E, an ap-

erture to be tapped for the insertion of an ordinary fuse, for the explosion of the powder in chamber B; D, the sabot screwed into the rear end of the shell, all for the purpose as hereinafter described.

It will be observed that the bars C are firmly dovetailed in and around the main body of the shell A, and are secured in that manner by casting bars C, first in separate molds, then arranging and securing the same in a cylindricel form by driving a ring over them, and placing them in the mold, (that is prepared to cast the body A,) when the metal is poured in, securing the bars to the body in the manner shown. By securing the bars in this manner they are held more firmly, and, by reason of the shell being made entirely of iron and not manipulated upon the lathe, is more economically constructed.

What I claim, and desire to secure by Letters Patent, is—

Securing the bars C around the body of the shell A, in the manner described, and for the purpose specified.

THOMPSON D. HART.
